FIG. 1

FIG. 1 is a perspective view taken from the left side of a swather embodying my new design;

FIG. 2 is a perspective view taken from the right side thereof;

FIG. 3 is a rear perspective view thereof with the adjusting crank lever omitted for convenience of illustration;

FIG. 4 is a front perspective view thereof;

FIG. 5 is a sectional view of the rear portion thereof, taken on a vertical plane through the line 5-5 of FIG. 3; and

FIG. 6 is a top plan view thereof.

I claim:

The ornamental design for a swather, as shown.
